HANDLE AND FRAME FOR DRESSER SET
UTENSILS AND THE LIKE

William Steinen, South Orange, N. J.

Application December 14, 1937, Serial No. 179,642

7 Claims. (Cl. 88—102)

The present invention relates to handles and frames for dresser sets and the like and particularly relates to handle and frame constructions for mirrors, brushes and other articles utilized in connection with the toilet and dressing sets.

It is among the objects of the present invention to provide an improved frame and handle construction which may be particularly applied to mirrors, brushes and other articles useful in 10 toilet or dresser sets, in which the mirror back and handle will be formed or contained in a frame which may be inexpensively and readily manufactured by relatively simple dies at a high rate of production and without the necessity of 15 using soldered joints or unnecessary finishing operations.

Another object of the present invention is to provide an improved toilet or dresser set utensil frame and handle construction which will be 20 rigid and strong, yet of inexpensive and light construction and which, in spite of its rugged character will be pleasing in appearance and will be decorative and ornamental.

Other objects will be obvious or will be apparent 25 during the course of the following specification.

In accomplishing the above objects, it will be found most suitable, according to one embodiment of the present invention, to form the frame 30 of U or V shaped integral channel rim members which continue without break from the frame into the handle portion.

Preferably, these channel members are bent to a desired polygonal or circle contour to receive 35 the mirror or back of the brush and the backing plate or frame and to form the sides of the handle.

If desired, the channel members may be split at the top of the frame and at the end of the 40 handle and the ends thereof drawn together by suitable clips or fastening means preferably of ornamental form.

Enclosed in and clamped at its periphery by the 45 channel members in the frame, in addition to the mirror or back of the brush, is a supporting plate which may be made of metal or of heavy fibre or cardboard stock. The plate may have an integral extension into the handle portion or it may be provided with a rod or strip of metal spot 50 welded or riveted to the central portion thereof, which rod or strip of metal will extend into the handle section.

The handle is relatively narrower than the 55 frame and it may be either straight or rounded or bulged at its outer end. The two channel

members closely face each other in the handle and grip the extension of the metal or stiff paper back plate and also reinforcing metal facing or other members which may be desirably placed in the body of the handle.

The present invention is particularly directed to the manner in which said channel member may be tightly gripped both upon the handle and upon the mirror or brush back and the iron or metal backing plate without the necessity of 10 utilizing pull rods extending through the handle member or any other tightening means which are designed to pull the handle and the backing plate together by screwing up elements on or associated with the handle member.

It is among the further objects of the present invention to provide an improved construction which will enable the channel members to be tightly forced upon the elements contained within the handle and the frame without screw 20 threads, nuts, bolts or other elements, which cause undue expense and manufacture and increase the cost of the assembly, and which, at the same time, will assure a permanent assembly 25 which will not tend to become disengaged or loosened even though subjected to considerable handling.

The present application is a continuation in part of application, Serial No. 110,831, filed November 14, 1936, and is continued in part in application, Serial No. 192,690, filed February 26, 1938.

In accomplishing these last mentioned objects, it has been found most satisfactory to form the frame either of one piece or of two pieces and to 35 assemble the handle plates, the backing plate or the mirror or brush back therein while the channel members at the throat or at the point of connection between the frame and the handle will be relatively loose and in untightened position.

The channel members extending from the top of the frame to the end of the handle should preferably be integral and these channel or rim members are permanently joined together at the 45 top of the frame and at the end of the handle.

To tighten the channel members and form a permanent rigid connection, which will not tend to break at the throat, a flaring throat sleeve is either pressed up upon the handle from the bottom thereof to draw the throat portions of the channel members together, or a split sleeve is placed around the throat and connected together.

Tongues or tabs on the throat sleeve construction are stamped into position to grip the frame 55

elements and assure a permanent connection which will not loosen with usage.

In the drawing which shows some of the various possible embodiments of the present invention but to which the invention is by no means restricted since many changes and modifications may be made therein all within the scope of the present invention.

Figure 1 is a front elevation of the complete assembly showing the portion of the frame in section.

Figure 2 is a longitudinal sectional view on the line 2—2 of Figure 1.

Figure 3 is a fragmentary side elevation upon enlarged scale upon line 3—3 of Figure 1.

Figure 4 is a transverse sectional view upon the line 4—4 of Figure 3.

Figure 5 is a transverse sectional view of the handle upon the line 5—5 of Figure 1 upon a somewhat enlarged scale as compared to Figure 1.

Figure 6 is a longitudinal sectional view of the end of the handle upon the line 6—6 of Figure 2 and upon a somewhat enlarged scale as compared with Figure 2.

25 Referring to Figure 1, the channel member A which may be of V shape or U shape, is shown as being formed of two symmetrical elements B which are formed at C of oval shape to enclose a mirror D and a backing plate E.

30 The integral extensions F form the sides of the handle G.

The ends of the frame elements B are locked together at the top of the frame E by the element H and at the end of the handle by the element I.

35 The throat element J is positioned upon the handle at the point of connection of the oval frame E and the handle G.

40 The side elements B are normally pressed out from flat brass or aluminum metal in the form of a straight channel of U or V contour and these channels are then stamped out and cut to form the frame element A.

45 If desired, the frame and handle elements consisting of the portions F and C may be formed in one piece, but in the construction shown, the elements are split, as indicated at 10, into two complementary or symmetrical elements C which are tied together at the top of the oval frame E by the element H.

50 The element H is provided with the tongues 11 which fit into openings 12 in the outside face or base 13 of the channels B.

Enclosed between the two portions C of the 55 frame A is the mirror D with bevelled edges 14 and the backing support plate 15 which may be of metal, hard fiber, cardboard, and so forth.

Between the backing plate 15 and the mirror D is the flexible material indicated diagrammatically at 16, said backing material permitting flexibility and preventing direct contact between the mirror D and backing plate 15.

60 The backing plate 15 may be covered by Celluloid or paper, if of metal, and said paper or Celluloid may have an extension down into the handle G, if desired.

70 The backing plate 15 may be provided with a riveted or spot welded rod or strip which extends into and forms a part of the handle G, but in the embodiment shown the backing plate 15 is provided with an integral extension 17 having the full width of the handle, which extends between the inside recesses 18 of the channel extensions F.

75 Corresponding to the mirror D, the handle G

preferably receives a metal or fiber plate 19 which is pressed closely against the extension 17 by the flanges 20 of said channel F.

The ends of the channels F and of the strips 17 and 19 are held together at the end of the handle G by the cap I which is provided with a domed bottom 21 and the side elements 22 which have the inturned tongues 24 fitting in the openings 25 in the bases 26 of said channels F.

It will be noted that the bottom of the cap is 10 shouldered at 27 to contact the lower ends 28 of the elements.

When the assembly so far described is made, the frame elements B will not as yet have been drawn tightly upon the mirror D, the plate 15 and 15 the handle elements 17 and 19.

As indicated by the dotted line 30 in Figure 4, the frame elements B at the throat will extend slightly beyond their final dimension.

To draw in the throat portions 31 of the frame 20 elements D, the throat sleeve element J is pressed upwardly upon the handle G.

The throat element J may be placed upon the handle assembly before the cap I is attached or it may be of sufficient size as to slide over the 25 cap I.

Where the handle assembly G, however, is of bulging contour or of irregular shape, it is desirable to split the throat collar J at the side 62 indicated at Figure 3 and have tongues extending therefrom into the base 18 of the channel F to lock the throat in position.

The throat J when in position, as shown in Figures 1 to 3, should draw the throat portions of the frame from the dotted line position 30 to 35 the solid line position 31 to tighten the entire structure.

To hold the throat element J permanently in position, the tongues 32 may be turned inwardly to extend into the openings 33 in the base 18 of 40 the channel portions C or the tab portions 35 are bent inwardly to engage the inner edge 66 of the rim or frame portions B.

The sides of the throat element J are bulged, as indicated at 36.

45 If desired, the tongues 32 may be omitted and the throat portion might be held in position solely by the inturned tab portions 35.

The construction which finally results will be permanent and rugged, will be of relatively light 50 weight and will be inexpensive to manufacture.

It will be noted that it is altogether devoid of screw machine parts, nuts and bolts and that it may be made entirely of stampings or shaped flat metal elements.

55 Moreover, the construction is artistic, decorative and ornamental and the frame construction A lends itself both to mirrors and to brushes of varying sizes and shapes for general use.

The oval shape of the frame E may be considerably varied so that such frame E may be square, trapasoidal, hexagonal, round, and so forth.

60 It will be particularly noted that the channel members extend integrally from the end of the handle G to the top of the frame C, and if desired, the split 10 might be eliminated by causing an integral connection of the sheet metal member forming the structure A.

Although the throat J is shown in one piece it 70 is obvious that it might be made in two pieces and, if desired, other means inside of the throat may be utilized for drawing up the throat portions 31 from the dotted line position to the solid line position indicated in Figure 4.

The handle G instead of being flat might also be made of oval or tubular cross section and the channel portions F might be extended so that they will contact at their inside edges or they 5 might be shaped so as to give an oval or circular handle.

It is apparent that the specific illustrations shown above have been given by way of illustration and not by way of limitation and that the 10 structures above described are subject to wide variations and modification without departing from the scope or intent of the invention, all of which variations and modifications are to be included within the scope of the present invention. 15

What is claimed is:

1. A frame and handle assembly comprising resilient side channel members, with the open channels facing each other, said channels being 20 spaced to provide a widened frame receiving a face element and a back plate of the same contour as the face element, the peripheries of which are received in, and held by the sides of said channel members and said channels converging 25 together to form a throat and then continuing side by side to form a handle, said handle including an extension of said back plate, said handle also including a reinforcing plate extending the full width and length of said handle, said 30 channel members being connected together, and means independent of said back plate extension consisting of a ferrule throat member encircling and contacting the channels at the base of the throat where they converge and causing contraction 35 together of said channel portions at the narrow base of the throat drawing up said side channel members tightly together upon said face element and said back plate, said ferrule being locked in position to said channel members at said throat.

2. A frame and handle-mirror combination comprising resilient channel rims positioned side by side with the open portions facing, substantially spaced to form the sides of a frame, then converging to form the sides of a throat and 45 finally closely spaced to form the sides of a handle, a mirror and a backing plate of similar contour having an extension through said throat into said handle, said handle also including a reinforcing plate extending the full width and 50 length of said handle, the peripheries of which mirror and plate are tightly held in the open portions of the sides of the frame, said rims being connected at the top of the frame and the end of the handle, and means consisting of a ferrule throat member 55 encircling and contacting the channels at the base of the throat where they converge and causing contraction together of said channel portions at the narrow base of the throat reinforcing the throat and tightening said rims upon said mirror and plate independent of said back plate extension, said back plate extension consisting of a plate tightly held between said handle sides, said ferrule being locked in position to said channel members at said throat.

3. A frame and handle assembly comprising 60 resilient side channel members, with the open channels facing each other, said channels being spaced to provide a widened frame receiving a face element and a back plate of the same contour as the face element, the peripheries of which 65 are received in, and held by the sides of said channel members and said channels converging together to form a throat and then continuing side by side to form a handle, said handle including an extension of said back plate, said channel 70 members being connected together, and means independent of said back plate extension to draw said side channel members tightly together upon said face element and said back plate, including a flared throat sleeve pressing 75

members being connected together, and means to reinforce said throat consisting of a ferrule throat member encircling and contacting the channels at the base of the throat where they converge and causing contraction together of 5 said channel portions at the narrow base of the throat and a narrow elongated plate tightly held between the portions of channel members and extending past into said throat, said ferrule being locked in position to said channel members 10 at said throat.

4. A frame and handle-mirror combination comprising resilient channel rim members positioned side by side with the open portions facing, substantially spaced to form the sides of a frame, 15 then converging to form the sides of a throat and finally closely spaced to form the sides of a handle, a mirror and a backing plate of similar contour having an extension through said throat into said handle, the peripheries of which mirror and plate 20 are tightly held in the open portions of the sides of the frame, said rims being connected at the top of the frame and the end of the handle, and means to reinforce the throat and to tighten said rims upon said mirror and 25 plate independent of said back plate extension, including a flared throat sleeve provided with inturned tang means to engage said channel rims on said frame beyond said throat, said throat sleeve constituting a ferrule which encircles, 30 contacts and causes contraction of said channel members at the constricted portion of the throat and serving to draw said channel members tightly together upon said frame and upon said handle, said ferrule being locked in position to said 35 channel members at said throat.

5. A frame and handle-mirror combination comprising resilient channel rims positioned side by side with the open portions facing, substantially spaced to form the sides of a frame, then 40 converging to form the sides of a throat and finally closely spaced to form the sides of a handle, a mirror and a backing plate of similar contour having an extension through said throat into said handle, the peripheries of which mirror and plate 45 are tightly held in the open portions of the sides of the frame, said rims being connected at the top of the frame and the end of the handle, and means consisting of a ferrule throat member encircling and contacting the channels at the base 50 of the throat where they converge and causing contraction together of said channel portions at the narrow base of the throat reinforcing the throat and tightening said rims upon said mirror and plate independent of said back plate extension, said back plate extension consisting of a plate tightly held between said handle sides, 55 said ferrule being locked in position to said channel members at said throat.

6. A frame and handle assembly comprising 60 resilient side channel members, with the open channels facing each other, said channels being spaced to provide a widened frame receiving a face element and a back plate of the same contour as the face element, the peripheries of which 65 are received in, and held by the sides of said channel members and said channels converging together to form a throat and then continuing side by side to form a handle, said handle including an extension of said back plate, said 70 channel members being connected together, and means independent of said back plate extension to draw said side channel members tightly together upon said face element and said back plate, including a flared throat sleeve pressing 75

the side channel members together at the throat, said throat sleeve constituting a ferrule which encircles, contacts and causes contraction of said channel members at the constricted portion 5 of the throat and serving to draw said channel members tightly together upon said frame and upon said handle, said ferrule being locked in position to said channel members at said throat.

7. A frame and handle assembly comprising re-
10 silent side channel members, with the open channels facing each other, said channels being spaced to provide a widened frame receiving a face element and a back plate of the same contour as the face element, the peripheries of which
15 are received in, and held by the sides of said channel members and said channels converging

together to form a throat and then continuing side by side to form a handle, said handle includ-
ing an extension of said back plate, said chan-
nel members being connected together, and
means independent of said back plate extension 5
consisting of a ferrule throat member encircling
and contacting the channels at the base of the
throat where they converge and causing contrac-
tion together of said channel portions at the
narrow base of the throat to draw said side chan-
nel members tightly together upon said face ele-
ment and said back plate, said ferrule being
locked in position to said channel members at
said throat.

WILLIAM STEINEN. 15
